HUGH BIDDULPH, OF COVENTRY, ENGLAND, ASSIGNOR TO COURTAULDS LIMITED, OF LONDON, ENGLAND

WINDING OF THREADS AND IN APPARATUS THEREFOR

Application filed April 7, 1931, Serial No. 528,439, and in Great Britain April 14, 1930.

This invention relates to the winding of threads on pirns, tubes and the like, and is particularly concerned with the method of winding in which the pirn or tube, on to which the thread is wound merely rotates, but does not receive any reciprocating motion, while a separate traverse motion is employed to cause the thread to assume the customary layers on the pirn or tube. It has hitherto been usual to employ for the traverse motion a reciprocating piece fitted with a thread guide consisting of a small wheel, over which the thread runs, the said wheel being so arranged that its axis is parallel with the axis of the pirn or tube onto which the thread is being wound. I have found that when such winding apparatus is employed for winding onto a pirn or tube artificial silk, which contains only a small twist, for example, two or three turns per inch, the twist is liable to be displaced, so that some parts of the thread are more twisted than other parts, and the variations in the twist of the thread are more or less periodic.

I have now found that I can obtain improved results as regards twist variation, when winding thread on to a pirn or tube when the said pirn or tube merely rotates, while the traverse motion is effected by a separate reciprocating piece of the apparatus, if the reciprocating thread guide which leads the thread on to the pirn or tube consists of, or comprises, two spaced grooved wheels over which the thread passes, the axes of said wheels being parallel and their common plane being at right angles to the axis of the pirn or tube.

In the accompanying diagrammatic drawing Figure 1 illustrates in front elevation and Figure 2 in side elevation so much of a pirn-winding apparatus, as is necessary to illustrate a method of carrying out the invention in practice but the invention is not restricted thereto. In these figures, A represents the thread which is leaving the bobbin B and passing over a compensating roller C and past a contact breaker D, this contact breaker being of the usual, or any suitable type, which automatically stops the motion of the pirn and traverse when the

thread breaks. After passing the said contact breaker D, the thread A passes over two small wheels E and F, and thence to a pirn G. As shown in Figure 1 the small wheels E and F are mounted on shafts carried on a piece H, which, by suitable means, is caused to reciprocate in a path parallel with the shaft of the pirn G. As is clearly seen from the drawing, the axes of the two small wheels E and F are at right angles to the axis of the pirn G. I have found that when working according to this invention, the thread on the pirn or tube is less liable to have periodic variations of twist than when the thread is passed over a guiding wheel the axis of which is parallel with the axis of the pirn, or tube.

What I claim is:

In an apparatus for the winding of threads, a reciprocating thread guide for leading the thread on to a pirn or tube, comprising two spaced grooved wheels over which the thread passes in succession, the axes of said wheels being parallel and their common plane being at right angles to the axis of the pirn or tube, said wheels being fixedly mounted in relation to one another upon a reciprocating member.

In testimony whereof I have signed my name to this specification.

HUGH BIDDULPH.
